US0D1097746S

(12) **United States Design Patent** (10) Patent No.: **US D1,097,746 S**
(45) Date of Patent: ** Oct. 14, 2025

(54) **TWEEZER WITH INTERCHANGEABLE TIP**

(71) Applicant: **ATELEI ENGINEERING SLU**, Irun (ES)

(72) Inventor: **Ivan Piquer**, Gipuzkoa (ES)

(**) Term: **15 Years**

(21) Appl. No.: **35/521,850**

(22) Filed: **Jun. 21, 2024**

(80) **Hague Agreement Data**

Int. Filing Date: **Jun. 21, 2024**

Int. Reg. No.: **DM/238750**

Int. Reg. Date: **Jun. 21, 2024**

Int. Reg. Pub. Date: **Aug. 2, 2024**

(51) **LOC (15) Cl. 08-05**

(52) **U.S. Cl.**

USPC **D8/30; D15/144; D15/144.2**

(58) **Field of Classification Search**

USPC D8/30, 71; D15/144, 144.1, 144.2

CPC B23K 1/00; B23K 1/0008; B23K 3/026

(57) **CLAIM**

The ornamental design for a tweezer with interchangeable tip as shown and described.

DESCRIPTION

1. Tweezer with interchangeable tip

1.1 : Front

1.2 : Right

1.3 : Top

1.4 : Bottom

1.5 : Perspective

1.6 : Perspective

1.7 : Perspective

1.8 : Perspective

The claimed design concerns a hand tool with rechargeable battery for precise part handling; reproduction 1.1 is a front view of the claimed design; reproduction 1.2 is a right side view thereof; reproduction 1.3 is a left side view thereof; reproduction 1.4 is a bottom view thereof; reproduction 1.5 is a first perspective view without a tip in place; reproduction 1.6 is a second perspective view without a tip in place; reproduction 1.7 is a third perspective view with a tip in place; reproduction 1.8 is a fourth perspective view with a tip in place.
